UNITED STATES PATENT OFFICE.

HENRY J. SCHMICK, OF HAMBURG, PENNSYLVANIA.

LIFTING-JACK.

SPECIFICATION forming part of Letters Patent No. 768,821, dated August 30, 1904.

Application filed April 5, 1904. Serial No. 201,696. (No model.)

To all whom it may concern:

Be it known that I, HENRY J. SCHMICK, a citizen of the United States, residing at Hamburg, in the county of Berks and State of Pennsylvania, have invented certain new and useful Improvements in Lifting-Jacks; and I do hereby declare the following to be a full, clear, and exact description of the invention, such as will enable others skilled in the art to which it applies to make and use the same.

My invention relates to lifting-jacks, and has for its object the application of a high degree of power without sacrificing time and sustaining the weight of the article being raised without the use of additional or extraneous mechanism; and the invention consists in certain improvements in construction, which will be fully disclosed in the following specification and claims.

In the accompanying drawings, which form part of this specification, Figure 1 represents a vertical section on line 1 1, Fig. 4, of a lifting-jack embodying my invention; Fig. 2, an end or face view of the disk and its working member detached; Fig. 3, a horizontal section on line 3 3, Fig. 4; and Fig. 4, an elevation partly in section.

Reference being had to the drawings and the designating characters thereon, 1 indicates the body or casing, having a base-plate 2, a vertical slot 3, a chamber 3', cylindrical in cross-section to receive the lifting-bar, and a detachable hood or cover 4, secured to the body by bolts 5 and provided with a shaft-bearing. The lifting-bar 7 is provided with a head 8, a toe-piece 9, which projects through the slot 3, and with toothed racks 10 on opposite sides of its transverse center.

11 indicates a gear-wheel having radial teeth 12 and pinions 13 13, which engage the racks 10 on the lifting-bar 7 to raise and lower the bar, and is mounted in bearings 15 15 on opposite sides of the body 1 and secured in position by a cotter-pin 16.

Within the hood or cover 4 is a revolute disk or head 17 at a right angle to the wheel 11 and on whose inner face is a radio-helical member 18, and to effect constant engagement of the working surface 19 of said member with

the teeth 12 said surface 19 is made angular in 50 transverse section of the member and of a constantly-increasing angle from the root or point of engagement 20 with a tooth, and the inner surface 21 of said member is inclined in the same ratio, but in reverse direction, to prevent 55 binding of the next tooth thereon as the disk revolves. This increasing incline or angularity of the member 18 causes the member to support the weight on the jack at any point in the travel of the lifting-bar 7 by engagement 60 of the teeth 12 of the wheel therewith and dispenses with the use of a ratchet and pawl for the purpose. The member 18 in the present instance has overlapping ends, with a space 65 22 between the ends for the passage of teeth 12, and two of said teeth are in constant engagement with the member 18, and in the revolution of the disk 17 all the teeth 12 are engaged consecutively. The disk 17 is provided with a shaft 23, supported in a bearing 24 on 70 the cover 4, and on said shaft is secured a ratchet 25 of any preferred construction for revolving the disk and raising and lowering the lifting-bar 7.

Having thus fully described my invention, 75 what I claim is—

1. A lifting-jack having a revolute disk provided with a working member on the face thereof, having a working surface of constantly-increasing angularity from the root of 80 the member outward, and a power-shaft supported in the casing of the jack; in combination with a revolute member having peripheral teeth engaged by said working member, pinions on the sides of the revolute member and 85 supported in said casing, and a vertically-movable member provided with toothed racks engaged by said pinions.

2. A lifting-jack having a revolute disk provided with a shaft, and a helical working 90 member on the face thereof, having a working surface of constantly-increasing angularity from the root of the member outward, a detachable cover inclosing said disk and supporting the shaft thereof; in combination with 95 a revolute member having peripheral teeth engaged by said working member, pinions on the sides of the revolute member, a shaft on

which said member and pinions are mounted, and a vertically-movable member provided with toothed racks engaged by said pinions.

3. A lifting-jack having a revolute disk
5 provided with a working member on the face thereof, having its sides inclined in reverse direction and forming a working surface of constantly-increasing angularity from the root of the member outward; in combination with a
10 revolute member having peripheral teeth engaged by said working member, and pinions

on the sides thereof, a shaft for said member supported in the casing of the jack, and a vertically - movable member provided with toothed racks engaged by said pinions.

In testimony whereof I affix my signature in presence of two witnesses.

HENRY J. SCHMICK.
